UNITED STATES PATENT OFFICE.

WILLIAM H. CLARK, OF ALBION, ASSIGNOR TO THE LOVELL MANUFACTURING COMPANY, LIMITED, OF ERIE, PENNSYLVANIA.

CASH REGISTER AND INDICATOR.

SPECIFICATION forming part of Letters Patent No. 444,391, dated January 6, 1891.

Application filed August 11, 1890. Serial No. 361,750. (No model.)

To all whom it may concern:

Be it known that I, WILLIAM H. CLARK, a citizen of the United States, residing at Albion, in the county of Erie and State of Pennsylvania, have invented certain new and useful Improvements in Cash Indicators and Registers; and I do hereby declare the following to be a full, clear, and exact description of the invention, such as will enable others skilled in the art to which it appertains to make and use the same, reference being had to the accompanying drawings, and to the letters and figures of reference marked thereon, forming part of this specification.

15 My invention consists in the improvements in cash indicators and registers hereinafter set forth and explained, and illustrated in the accompanying drawings, in which—

Figure 1 is a perspective view of my improved cash indicator and register, one of the side frames being left off and other parts broken away. Fig. 2 is a top or plan view of my improved cash indicator and register. Fig. 3 is a front view of same, partly in elevation and partly in section, on the line $x-x$ in Fig. 2, looking in the direction of the arrow. Fig. 4 is a detail view of a portion of the same. Fig. 5 is a transverse section of same on the line $y-y$ in Fig. 2, looking in the direction of the arrow. Fig. 6 is a detail view of the compound key-lever mechanism of my machine. Fig. 7 is a rear view of the same in elevation. Figs. 8 and 9 are detail views of portions of the same.

35 Like letters and figures refer to like parts in all the views.

In the construction shown of my improved cash indicator and register the frame consists of the sides A A, connected by a plate B, which 40 rests upon and is secured to a base B', in which the cash-drawer of the machine operates.

On a rod A' in the lower part of the sides A A of the frame are pivoted four groups of 45 key-levers C, C', C², and C³, the group C representing cents from one to nine, inclusive, the group C' multiples of cents from ten to ninety, inclusive, the group C² dollars from one to nine, inclusive, and the group C³ multiples of dollars from ten to ninety, inclusive.

In the vertical grooves b b b b in the face of the frame-plate B are vertically-sliding rack-bars D D' D² D³, on which are feet d, d', d², and d³, the feet d resting upon and being actuated by the group of key-levers C, the foot d' resting upon and being actuated by the group of key-levers C', the foot d² resting upon and being actuated by the group of key-levers C², and the foot d³ resting upon and being actuated by the group of key-levers C³, 60 each of said groups being adapted to operate the foot resting thereon and the rack-bar secured to such feet only.

To the rack-bars D, D', D², and D³ are secured racks a, a', a², and a³ and c, c', c², and c³, the racks a a' a² a³ respectively intermeshing with and actuating pinions e, e', e², and e³, secured to indicator-wheels E, E', E², and E³, respectively, said pinions and indicator-wheels being mounted on a rod F, secured in 70 bearings f on the upper part of the frame-plate B. The racks c, c', c², and c³ also respectively intermesh with segmental gears G, G', G², and G³ on the rear ends of one of the arms of the bell-crank levers g, g', g², and g³, 75 which bell-crank levers are mounted on sleeves h on a rod H, secured in bearings H' on the frame-plate B. On the rod H, adjacent to the ends of the sleeves h, are also mounted gear or ratchet wheels I, I', I², I³, and I⁴, each 80 containing sixty teeth, or any multiple of tens of teeth desirable.

On the outer ends of the arms i of the bell-crank levers g, g', g², and g³ are pivoted spring-actuated dogs J, J', J², and J³, adapted 85 to engage with the teeth of the wheels I, I', I², and I³ and actuate the same when the rack-bars D, D', D², and D³ are respectively being raised by the operation of the key-levers on the feet thereof, said dogs, however, passing 90 over the teeth in said wheels freely when said rack-bars are returning to their normal positions.

In bearings K on the rear side of the frame-plate B, nearly opposite the gear-wheels I, I', I², I³, and I⁴, I mount short shafts k, k', k², and k³, the shaft k extending from opposite the left-hand side of the gear-wheel I to opposite the gear-wheel I', and the shaft k' from the gear-wheel I' to the gear-wheel I², the shaft 100

k^2 from the gear-wheel I^2 to the gear-wheel I^3 , and the shaft k^3 from the gear-wheel I^3 to the gear-wheel I^4 , as and for the purpose herein-after set forth. Secured to the left-hand sides 5 of the gear-wheels I , I' , I^2 , and I^3 are six carrying-points l , equidistant from each other, one opposite each tenth tooth in said gear-wheels, and adjacent to the left-hand sides of said gear-wheels and carrying-points are registering wheels or disks L , L' , L^2 , L^3 , and L^4 , each of which is secured to one of said gear-wheels and moves in unison therewith. These 10 registering-wheels are also numbered on their peripheries with six series of figures from 1 to 0, inclusive, each of which series of figures commencing opposite to one of the carrying-points l on the gear-wheel adjacent thereto. 15 On the end of the shaft k , opposite the carrying-points l on the gear-wheel I , is adjustably secured a laterally-projecting arm or lever M , adapted to be engaged by the carrying-points l on the gear-wheel I as it rotates the rock-shaft k , and on the opposite end of the shaft k , opposite the gear-wheel I' , is a downwardly-projecting lever or arm N , having pivoted thereto a dog n , engaging with the teeth in the gear-wheel I' , so that the rocking of the shaft k by the engagement of the carrying-point l on the gear-wheel I moves the lever N , and the dog n pivoted thereto, and engaging with the teeth in the gear-wheel I' , so as to carry the gear-wheel I' forward one tooth. Likewise on the end of the shaft k' is secured a like adjustable arm or lever M' , adapted to 20 engage with the carrying-points l on the gear-wheel I' , and on the opposite end of the said shaft k' is secured a like lever N' , carrying a dog n' , engaging with the teeth on the gear-wheel I^2 , and on the end of the shaft k^2 a like lever M^2 , adapted to engage the carrying-points l on the gear-wheel I^2 , and on the opposite end of the shaft k^2 a like lever N^2 and dog n^2 , engaging with the teeth of the gear-wheel I^3 , and on the end of the shaft k^3 a like lever M^3 , adapted to engage the carrying-points l on the gear-wheel I^3 , and on the opposite end of the shaft k^3 a like lever N^3 and dog n^3 , engaging with the teeth of the gear-wheel I^4 , each of which series of shafts and 25 the mechanism thereon operate in like manner as does the shaft k and levers M and N and dog n connected therewith, first herein-before described, and by means of which when the wheel I is moved forward ten teeth the wheel I' is carried forward one tooth, and likewise the carrying forward of the wheel I' ten teeth moves the wheel I^2 forward one tooth, and so on throughout the whole series, thus carrying by tens from the right to the left of 30 said series of registering-wheels.

On the rear side of the frame-plate B below the shafts k , k' , &c., are bearings K' , in which bearings are pivoted dogs O , which project forward through openings in the frame-plate B beneath the gear-wheels I , I' , I^2 , and I^3 , with the teeth of which gear-wheels said dogs are adapted to engage, and in vertical slides o on

the back side of the frame-plate B below said dogs O are vertically-sliding plates P , P' , P^2 , and P^3 , one of said plates resting upon each of said groups of key-levers C , C' , C^2 , and C^3 , so as to be actuated thereby. On the upper edge of each of said plates is also secured an upwardly-projecting lug p , adapted to contact with and raise the dog O corresponding therewith into engagement with the gear-wheels L or L' , &c., as the case may be, when the plate having such lug p thereon is raised by the operation of the key-levers of the group upon which it rests. On the plates P , P' , P^2 , and P^3 are also secured wedge-shaped projections q , q' , q^2 , and q^3 , and on a bar Q , which is secured between the side frames A A at the rear of the frame-plate B and the vertically-sliding plates P , P' , P^2 , and P^3 , are horizontal bearings or guides R . (See Figs. 7 and 8.) In these guides R are short horizontally-sliding bars R' , R^2 , and R^3 , said bars being of sufficient length to reach from one of the wedges q to another near the inner ends of the bars R' and R^3 . I place pins r and r' therein, which operate to limit the lateral movement of all of said bars, so that if one of the wedges q be raised by movement of one of the plates P it will push all of the bars together and toward the left until the pins r , r' contact with the guides or bearings R adjacent thereto, and so long as the wedge q remains in that position none of the other wedges q' , q^2 , or q^3 can be raised so as to pass between the ends of the bars adjacent thereto, and in like manner the raising of either of the wedges q' , q^2 , or q^3 operates to move the bars R , R^2 , and R^3 laterally, so as to prevent the raising of any of the other wedges. Thus 35 the raising of each wedge operates to lock or prevent the raising of all the others until it is lowered back to its normal position, and as the plate P and wedge q thereon are operated only by the group C of the key-levers, and each of the other plates and wedges described are likewise each operated by a single group of key-levers only, it is manifest that keys in but one group can be depressed at the same time, as the operation of keys in one group operates 40 through the mechanism described to lock for the time such key or keys are depressed the keys in all the other groups.

It will be observed that the outer end of the bar R' and both ends of the bar R^2 and the outer end of the bar R^3 have short sections r^2 hinged thereto in such a manner that as the wedges pass upward they will remain rigid, but will yield as the wedge falls back to its normal position, the object of this construction being to prevent the wedge sticking, a small spring r^3 operating to return the hinged portion r^2 back to its normal position when the wedge has been withdrawn.

Across the lower part of the machine, near the rear edges of the side frames A A , I place a rod S , which operates as a rest for the rear ends S' of the key-levers, and somewhat above the rod S and in the frame at the rear ends

S' of the key-levers I place a rod T, upon which I mount supplementary levers T', one of which is coupled to each of the key-levers representing cents from one to four, inclusive, 5 in the group C, and from ten to forty in the group C', and from one dollar to four dollars in the group C², and from ten dollars to forty dollars in the group C³, for the purpose of more nearly equalizing the movement or traverse 10 of said key-levers with the traverse of the remaining key-levers, as hereinafter described. The outer ends of these supplementary levers T' are coupled each to its respective key-lever at a point t between the axis A' 15 of the key-levers and the feet d, d', d², and d³ of the rack-bars D, D', D², and D³ at such varying distances as may be required to equalize their movement, the said key-levers to which said supplementary levers T' are coupled 20 being cut away beneath the feet d, &c., of the rack-bars, so that the feet of the rack-bars rest upon the supplementary levers T', so that when the rear end of the rack-bar is raised the supplementary levers T' act upon 25 the foot of the rack-bar to raise it in lieu of the key-lever itself, as in other cases where the key-lever is not provided with a supplementary lever T', thus allowing a much greater traverse of the key-lever than would 30 otherwise be possible, this operation being fully illustrated by the full and dotted lines in Fig. 6. On the key-levers at the rear of the rack-bar feet d, d', d², and d³ are projections U, curving toward the rear faces of 35 said rack-bar feet, these projections being of different lengths, as illustrated in Fig. 5, according to the distances of the traverse of the several key-levers, and are adapted to enter depressions V in the rear faces of the rack-bar feet when raised and lock the rack-bar foot in such position until the key-lever is released. They also operate to prevent the rack-bar from being thrown up too far by a sudden or sharp blow upon the key-lever. 40 The said curved projection U on the key-lever also engages with the lower edges of the vertically-sliding plates P, P', P², and P³, operating the same, together with the locking mechanism thereon, hereinbefore described. 45 On each edge of the rack-bars D, D', D², and D³, below the racks thereon, are ratchet-teeth 1 and 2, in which dogs 3 and 4 operate, these dogs 3 and 4 being coupled together by means of spiral retracting-springs 5, which 50 operate to normally force the dogs 3 and 4 into contact with the ratchet-teeth 1 and 2. Across the front of the machine in front of dogs 3 and 4 is a horizontally-moving bar 6, the ends thereof being pivoted to one of the 55 arms 7 of the bell-crank levers 8 and 9, pivoted to the face of the frame-plate B of the machine, so that the movement of said bell-crank levers operates to move the bar 6 back and forth across the front of the machine. 60 On the bar 6 are pins 10 and 11, which engage with like pins 12 and 13 in the dogs 3 and 4, by means whereof the movement of the bar

6 to the right or left serves to move the dogs 3 and 4 in and out of engagement with the teeth 1 and 2 on the rack-bars, as hereinafter set forth. Centrally on the faces of the rack-bars D, D', D², and D³ are vertical V-shaped projections 14, and on the rear of the rod or bar 6 are spring-hooks 15, (see detail view, Fig. 4,) the vertical projections 14 extending upward 70 on the rack-bars just far enough so that when the rack-bars are at their lowest point the hooks 15 will pass the upper ends thereof, but will engage therewith when raised above that point. 75

8c

To the arms 16 of the bell-crank levers 8 and 9 are coupled downwardly-projecting links 17 and 18, the lower ends of which are pivoted to releasing-levers 19 and 20, pivoted on the rod A' at each side of the machine, the outer ends of which levers being connected together by a cross-bar 21 in front of the keys. 85

It will be observed that the dogs 4 are at all times normally engaged with the teeth 2 on the rack-bars, except during the times the rack-bars are returning to their normal positions. This is accomplished by depressing the releasing-levers 19 and 20, which operate the bell-crank levers 8 and 9, so as to move the horizontal bar 6 to the right, which operation releases the dogs 4 from the teeth 2 in the rack-bars and at the same time moves the hooks 15 into engagement with the vertical ribs 14 on the rack-bars, which prevents the re-engagement of the dogs 4 with the teeth 2 in the rack-bars until the rack-bars have passed to their lowest point, when the upper ends of the vertical ribs 14 pass below said hooks 15, which allows the sliding bar 6 to move back toward the left to its normal position, with the dogs 4 again in engagement with the teeth 2 on the rack-bars. The inner ends 22 of the releasing-bars 19 and 20 are also turned downward and pass through openings in the base B', where they engage with the spring-catches 23 at the rear end of a cash-drawer 24, mounted in the base of the case of the machine, and operate to retain the cash-drawer 24 in a closed position until released by depressing the outer ends 110 of said releasing-levers 19 and 20. In the bottom of the case, at the rear end of the cash-drawer 24, I also place a retracting-spring 25, which, when the drawer 24 is closed, is compressed and which operates when the drawer 115 is released by the operation of the releasing-levers 19 and 20 to throw the drawer 24 open. 120

To the left-hand side of the frame A A, I secure an alarm-bell 26 and also a pivoted hammer-lever 27, which has a spring-catch 28, 125 adapted to engage with a pin 29 on the link 17. When the releasing-levers 19 and 20 are depressed, the hammer 31 is drawn back from the bell, and when they are released the retracting-spring 30, secured to the bell-hammer lever 27, causes it to strike the bell 26 and sound an alarm, which is done each time the releasing-levers 19 and 20 are depressed. 130

In operation the depressing of any one of

the key-levers in the groups C C' C² C³ thereof raises the rack-bar foot and rack-bar thereon far enough to turn the indicating and registering wheels connected therewith the proper 5 distance to indicate and register the amount designated by said key, and at the same time operates the carrying mechanism so as to carry forward by tens, when necessary, so that each amount indicated by the key or keys o depressed is indicated on the indicator-wheels and at the same time added to the aggregate amount previously indicated and registered.

The further description of the operation of the other parts of the mechanism having been 15 hereinbefore fully described and set forth in the description thereof, further description is deemed unnecessary; therefore

What I claim as new, and desire to secure by Letters Patent of the United States, is—

20 1. The combination, in a cash indicator and register, of a group of key-levers, some of which are direct and some of which are compound, with a rack-bar foot resting on all of said key-levers, a vertically-moving rack bar 25 secured to said rack-bar foot, and indicating and registering wheels geared to and operated by said rack-bar, substantially as and for the purpose set forth.

2. The combination, in a cash indicator and 30 register, of main key-levers and supplementary levers coupled to some of said main key-levers, with rack-bar feet resting upon and adapted to be operated both by the key-levers without supplementary levers and also by 35 the supplementary levers coupled to others of said main key-levers, substantially as and for the purpose set forth.

3. The combination, in a cash indicator and 40 register, of key-levers, both simple and compound, a rack-bar foot resting upon and operated both by said simple and said compound key-levers, with a vertically-sliding locking-plate adapted to be operated by the rear ends of said levers, and hooked projections on the 45 rear ends of said key-levers adapted to engage depressions in the rear faces of the rack-bar

feet when the key-levers are fully depressed, substantially as and for the purpose set forth.

4. The combination, in a cash indicator and 50 register, of a group of key-levers, a rack-bar foot resting upon all of said group and adapted to be actuated by each lever of said group independently of the others, and registering and indicating wheels actuated by a rack-bar secured to said rack-bar foot, with a vertically-sliding locking-plate resting on the rear ends 55 of all of the key-levers of such group and adapted to be raised thereby, and a dog pivoted to the machine-frame and adapted to be forced into engagement with the teeth of 60 the registering-wheel by said locking-plate when raised by the operation of any of the key-levers, substantially as and for the purpose set forth.

5. The combination, in a cash indicator and 65 register, of a series of two or more groups of key-levers and a rack-bar foot, and a vertically-sliding locking-plate resting upon each of said groups of key-levers, with a series of horizontally-sliding bars mounted in bearings 70 on the frame directly above said vertically-sliding locking-plates, and wedges on said locking-plates adapted to pass upward between the ends of said sliding bars, substantially as and for the purpose set forth. 75

6. The combination, in a cash indicator and register, of a key-actuated rack-bar, ratchet-teeth in the edges of said rack-bar, spring-actuated dogs operating in the teeth in the edges of said rack-bar, and a vertical rib on 80 the outer surface of said rack-bar, with a horizontally-moving rod having pins thereon engaging with pins on said spring-dogs, and spring-hooks adapted to engage with the rib on the face of said rack-bar, substantially as 85 and for the purpose set forth.

In testimony whereof I affix my signature in presence of two witnesses.

WILLIAM H. CLARK.
